UNITED STATES PATENT OFFICE

PLINY McOMBER AND OTIS H. McOMBER, OF MAPLE GROVE, MICHIGAN.

FENCE-POST.

SPECIFICATION forming part of Letters Patent No. 286,461, dated October 9, 1883.

Application filed June 15, 1883. (No model.)

To all whom it may concern:

Be it known that we, PLINY McOMBER and OTIS H. McOMBER, of Maple Grove, in the county of Barry and State of Michigan, have invented certain new and useful Improvements 5 in Fence-Posts; and we do hereby declare that the following is a full, clear, and exact description of the invention, which will enable others skilled in the art to which it appertains to make and use the same, reference being had 10 to the accompanying drawings, which form a part of this specification, and in which—

Figure 1 is a perspective view of a portion of a fence provided with our improved fence-post. Fig. 2 is a side view of the post. Fig. 15 3 is a vertical section of the same, and Figs. 4, 5, 6, and 7 are perspective detail views of the different manners of attaching the wires to the post.

20 Similar letters of reference indicate corresponding parts in all the figures.

Our invention has relation to metallic fence-posts; and it consists in the improved construction and combination of parts of the 25 same, as hereinafter more fully described and claimed.

In the accompanying drawings, the letter A indicates the body of the post, which is flat, tapering slightly toward the top, and tapering 30 to a sharp point toward the lower end. The edges of the upper portion of the post are provided with flanges B, provided with laterally-extending upwardly-bent lugs or fingers C and D, and the lower portion of the post, 35 which is intended to be inserted into the ground, is provided with two longitudinal ribs, E, extending from the central line of the same at right angles to the flat body of the post, which ribs are tapering toward the lower 40 end in the same manner as the lower portion of the post. The lugs or fingers C consist of a horizontal portion extending laterally from the flange of the post, and a short vertical upwardly bent portion, and are adapted to receive the fence-wires F, where continuous

45 wires are used in the notch formed between them and the flange of the post, and the wires are secured to the lugs by means of wire loops G, which are passed over the wire and under 50 the horizontal portion of the lugs, where they

are twisted firmly against the said lugs, as shown in Fig. 4. The lugs or fingers D consist, likewise, of a laterally-projecting horizontal portion and a vertical upwardly-bent portion; but the upwardly-bent portions of these 55 lugs are grooved around their upper ends, and adapted to receive the wires twisted around them, as shown in Fig. 5. The body of the post has a series of longitudinal slots, H and I, and there are beside every alternate slot 60 two perforations, J, one upon each side of said slot and one slightly above the above the other. These slots are used when the wires are fastened to the post, forming separate panels, the ends of the wires from one panel being inserted through the slots from one side and bent back through one of the perforations, 65 and the wires from the other panel being inserted through the slots in the same manner from the other side, and their ends being bent 70 in the same manner through the holes upon the other side of the slots, as shown in detail in Fig. 6. When it is desired, furthermore, to make the fence impenetrable for smaller animals, extra wires may be inserted through 75 the slots I, to one side of each of which slots is a bail, K, tapering toward the lower end, and the ends of these wires are bent at right angles to themselves, and inserted into the space between the bails and the body of the 80 post, and pressed down into the said space, the tapering shape of which will clamp the wires firmly, holding them in place.

Where metallic bands are used in making the fence, they may either be inserted in the 85 lugs D or they may be passed continuously through the slots H, secured by wire loops L, inserted through the perforations J over the bands, and having their ends twisted upon the other side of the perforations.

It will be seen by the foregoing description that this post may be used with many different ways of attaching the wires, which will adapt it particularly to be used where one construction of wire fence stops and another 95 construction commences, as is often the case, either where a place has been fenced at different times and by different persons or where the place adjoins another place, or in similar cases; and as the post by its construction is 100

very strong, and almost any material in the shape of flat or round fence-wire may be used with it, it will afford a very desirable and economical post.

5 Having thus described our invention, we claim and desire to secure by Letters Patent of the United States—

1. The combination of the post having the longitudinal slots, and having the downwardly-tapering bails at one side of the slots, with the wires having their ends inserted through the slots from both sides, and having their ends inserted into the tapering bails at the other side of the slots, as and for the purpose 15 shown and set forth.

2. A fence-post consisting of a flat body

having tapering and flanged lower end, having flanges upon its edges provided with upwardly bent lugs or fingers, longitudinal slots, perforations upon each side of every other slot, 20 and tapering bails upon both faces of the post at the side of the remaining slots, as and for the purpose shown and set forth.

In testimony that we claim the foregoing as our own we have hereunto affixed our signatures in presence of two witnesses.

PLINY McOMBER.
OTIS H. McOMBER.
